5 Claims. (Cl. 192—135)

1

The invention has reference to machinery guards for textile combing and other machines in which certain moving parts are shielded by means of a guard which is prevented from being displaced when the machine is in operation by an interlocking mechanism associating the guard with a "knock-off" handle or the like employed to stop the machine.

The present invention proposes, as an alternative form of the supplementary attachment by which the displacement of the guard is prevented so long as any parts of the machine are still running, to provide a detent operatively associated with a handle for releasing the guard and a friction coupling influenced by a principal rotary member of the machine, and connected to said detent in such manner that the detent is maintained in the engaged position preventing movement of said handle whilst said member is rotating, and released when said member comes to rest.

In the case of a combing machine the friction coupling may be operated by the brush shaft, the detent being carried on a lever which is urged towards the engaged position of the detent when the brush shaft rotates but is otherwise actuated by a counter-weight to pivot the lever in the opposite direction so as to disengage the detent and permit the guard handle to be moved to displace the guard.

One embodiment of the invention, as applied to a combing machine guard, is illustrated in and hereinafter described with reference to the accompanying drawing. In said drawing, which is a partly sectional elevation of part of a combing machine, the numeral 10 indicates the machine frame, 11 the comb cylinder shaft, 12 the top comb, 13 the bottom nipper, and 14 the brush shaft. The top-comb mechanism is protected, when the machine is in operation, by a guard 15 consisting of a boxlike member which is supported over the top nipper by arms 16 fixed on a shaft 17 which is pivotally supported by brackets 18.

Also mounted at 19 on an off-set 181 of each bracket 18 is a shaped abutment member 20 which, when the guard arm 16 is in the position occupied when the guard is in use, is adapted to engage a notch 161 in the boss 162 of said arm 16 so as to prevent a turning movement of the latter into the position, indicated in dotted lines, in which the guard 15 is raised clear of the comb mechanism. Said abutment member 20 is connected by a link 21 with a lever 22 which is fixed on a shaft 23. A lever 24 fixed on said shaft 23

5 is connected to a reciprocating rod 25 which is mounted to slide in a bearing 26 and the end 251 of which is adapted to register with a hole 271 in a bracket 27 carried by the setting-on rod 28. The arrangement is such that only when the rod 25 is in the position occupied when the abutment member 20 is in engagement with the guard arm 16, i. e. when the guard 15 is closed, can the setting-on rod 28 be moved endwise to set the machine in motion. Conversely, the guard 15 cannot be raised when the machine is in motion. A handle 29 is fixed on the shaft 23 for manual disengagement of the abutment member 20 when the machine is at rest and the setting-on rod 28 is in the position wherein it can be locked by the rod 25 to enable the guard 15 to be raised with safety.

20 The mechanism provided in accordance with the present invention, by which the guard 15 is prevented from displacement from the operative position except when the moving parts of the machine come to rest, comprises a friction coupling of which one part is constituted by a bushing 30 fixed upon the brush shaft 14, the other part of the coupling taking the form of a sleeve 32 fitted with a good running fit upon said bushing. The arrangement is such that the friction between the outer surface of the bushing 30 and the inner surface of the sleeve 32 tends to rotate the sleeve 32 in the same direction as the bushing 30 so long as the brush shaft 14 is rotating.

35 Slidably mounted in a position conveniently near to the coupling is a rod 33 the end of which is connected at 34 to a lever 35 on the shaft 23 so that the movement of the abutment member 20 to disengage the guard when the latter is in the operative position involves a longitudinal movement of said rod 33. The rod 33 carries a circumferentially grooved block 36. A lever 37 fixed to the sleeve 32 has its extremity 38 shaped as a finger of which the end is received in the groove 361 of the block 36 on said slidable rod 33, and the arrangement is such that when the brush shaft 14 is rotating the friction between the parts of the coupling serves to press the finger 38 on said lever 37 into said groove 361, thereby positively preventing the slidable movement of said rod 33 (which is essential to permit the displacement of the guard 15) before the brush shaft 14 has come to a standstill.

50 When the brush shaft 14 is no longer rotating, a counter-weight 39 serves to raise the finger 38 from the grooved block 36, disengaging the latter

2

55

and enabling the rod 33 to move when the guard is released.

A stop 40 is provided for limiting the movement of the lever 37 by said counter-weight 39. It will be understood that when the machine is started, which cannot occur until the guard 15 has been closed, the friction coupling will immediately operate to restore the lever 37 to the position engaging the block 36 on the slideable rod 33. A single attachment such as that herein-described may serve to control the several guards of a multi-head machine such as the conventional comb.

It will also be understood that the device is applicable to other machines where it is desired to prevent the displacement of a guard until all moving parts of the machine have come to rest.

What I claim as my invention and desire to secure by Letters Patent is:

1. A textile machine comprising, in combination, a movable guard, an abutment engageable with the guard for obstructing displacement of the guard when the machine is in operation, a handle for shifting the abutment to a non-obstructing position, and means for holding the handle stationary and inoperative when the machine is in operation comprising a principal rotary member of the machine which rotates continually so long as the machine is in operation, a friction coupling including an output member frictionally biased through the coupling in a definite direction in response to the rotation of said rotary member, a detent carried by the output member, means positively connected to the handle and adapted to be engaged and locked against movement by the detent, the construction and arrangement being such that the coupling maintains the detent thus effective so long as said rotary member continues to rotate, and means for automatically disengaging said detent when said rotary member comes to rest.

2. A combing machine comprising, in combination, a movable guard, an abutment engageable with the guard for obstructing displacement of the guard when the machine is in operation, a handle for shifting the abutment to a non-obstructing position, and means for holding the handle stationary and inoperative when the machine is in operation comprising the brush shaft of the machine which rotates continually so long as the machine is in operation, a friction coupling including an output member frictionally biased

through the coupling in a definite direction in response to the rotation of the brush shaft, a lever carried by the output member, a detent on one end of said lever, a catch, a catch supporting part connected to the handle, and a counterweight on said lever, the detent being maintained in engagement with said catch when the brush shaft is in rotation, and the counterweight serving to release the detent when the brush shaft comes to rest.

3. A combing machine as claimed in claim 2, wherein the coupling members are respectively a bushing fixed on the brush shaft and a sleeve rotatable on said bushing, the operation of the coupling depending upon the friction between the contacting surfaces of said bushing and sleeve when the latter is restrained from rotating with the former.

4. A combing machine as claimed in claim 2, 20 wherein the coupling members are respectively a bushing fixed on the brush shaft and a sleeve rotatable on said bushing, the operation of the coupling depending upon the friction between the contacting surfaces of said bushing and sleeve 25 when the latter is restrained from rotating with the former, and wherein a stop is provided for limiting reverse movement of said lever under the influence of the counter-weight when the brush shaft is at rest.

5. A combing machine as claimed in claim 2, 30 wherein the catch supporting part connected to the handle is a rod arranged to slide longitudinally when the handle is operated, and wherein the catch consists of a circumferentially grooved 35 block fixed on said rod, the groove of said block being capable of receiving the detent on the coupling lever when the latter is in the operative position.
